(57) **CLAIM**

The ornamental design for a combined vehicle waistline and fender vent, as shown and described.

DESCRIPTION

FIG. 1 is a front right perspective view of a combined vehicle waistline and fender vent according to the present invention.

FIG. 2 is a rear right perspective view thereof.

FIG. 3 is a front view thereof.

FIG. 4 is a rear view thereof.

FIG. 5 is a tight side view thereof; and,

FIG. 6 is a top view thereof.

The broken lines illustrate environmental structure which forms no part of the claimed design. A second embodiment, comprising of a mirror image of the combined vehicle waistline and fender vent on the opposite side of a vehicle, is claimed but not shown.
